BONELESS FOUNDATION GARMENT

Alice M. Rabensdorf, Cleveland, Ohio, assignor of
one-half to Sidney J. Sternberger, Indianapolis,
Ind.

Application March 8, 1937, Serial No. 129,574

3 Claims. (Cl. 2—36)

This invention relates to an undergarment generally designated as a foundation or corset, and has for its primary object the provision in such a garment for slenderizing the figure of the wearer without cutting in or wrinkling at the waistline and at the same time for even distribution and figure control through a concealed waistline and diaphragm reinforcement cooperating with an overlapping abdominal reinforcement which further aids in supplying support to the abdomen, preventing bulging or padding, all without use of boning in any manner or elastic to any major degree particularly in the upper and abdominal portions. A further feature of the invention is a provision in the underarm section of the garment for excess underarm and shoulder development.

These and other features of the invention will become more apparent to those versed in the art by reference to the following description of one form of the invention which is illustrated more or less diagrammatically in the accompanying drawings, in which

Fig. 1 is a front perspective view of a corset embodying the invention;

Fig. 2, a rear elevation; and

Fig. 3, a developed view of the inside of the upper portion of the corset.

Like characters of reference indicate like parts in the several views in the drawings.

The corset is formed exteriorly of some form of clinging material such as "rayon", silk, or cotton as desired. This material is cut into the two front panels 10 and 11 with the bust supports 12 and 13 respectively inserted in the upper ends. The panels are permanently joined such as by stitching through a small area at 14 and left separated from there downwardly to form the front, lower laced placket 15. From the junction at 14, the upper portions of the panels 10 and 11 are detachably joined by the usual and well known slideable fastener 16, popularly known as a "zipper", by pulling upwardly on the slide 17. The lateral edges of the panels 10 and 11 join respectively through side seams 18 with the side panels 19 and 20 which in turn join through up and down seams with the back panel 21. The materials of the side and back panels may be the same as that of the front panels 10 and 11. However, the lower portions of the side panels 19 and 20 are provided with elastic inserts 22 and 23 extending upwardly from the lower ends of the panels to a height substantially that of the front lower placket 15 whereby the opening 55 and closing of the placket through the lacing

may be in cooperation with the elasticity of those inserts enabling the snugly fitting lower portion of the garment to be put on and taken off without disturbing the lacing at 15.

The combined lateral width of the two front panels 10 and 11 is made to be such as to cover over the front of the figure between lines dropped downwardly from the forward sides of the arm-pits. Now to each of these panels 10 and 11, preferably on the inner face, is applied a roughly triangularly shaped piece of cloth 24 such as muslin or the like which is comparatively non-stretchable. This cloth 24 is applied to have the apex anchored in the side seam 18 at a position above the pelvic arch bone, and to have the base 15 of the triangle anchored along the central hem of the panel, whereby the cloth slopes around and upwardly from the side seam 18 centrally to or above the waistline to compress the abdomen but not extending over to compress the ribs, and also around downwardly and forwardly over and down under the abdomen but not opposite so as to compress the bones of the pelvis, and to extend by a narrow width to the lower end of the panel—a position well down on the thigh below the hip. 20 To complete the reinforcement of the area covered by the cloth 24, it is stitched to the panel by closely spaced lines of stitching of any suitable pattern, herein shown as by the upwardly and downwardly turned stitching leading from a horizontally disposed line, this form being particularly effective as a non-stretchable reinforcement, further aided when the weave in the panel and cloth are angularly disposed to one another. 30

This reinforced zone covers the abdomen, tying in at the sides and above, and providing support from below, and thus aids in smoothing out the figure contour without producing any bulging or padding.

However, to complete the figure control, a co- 40 operating feature is utilized.

This feature comprises essentially a one piece (may be made of scraps sewed together) belt 25 carried entirely within the garment and there positioned to pass around the waist line of the 45 figure. This belt 25 is provided with widened front ends that are anchored permanently in the front central hems of the panels 10 and 11, the ends extending downwardly to lap over (interiorly) substantially the upper half of the vertical 50 distance of the reinforcement 24 without attachment thereto other than along the hem of the panels.

At the outer rear sides of the bust supports, the belt 25 rises vertically upwardly free of the gar- 55

ment to its top edge and is there permanently united under the top finishing hem 26, the vertical rise being along the line of the seam 18. The belt 25 hangs freely within the garment from this top hem 26 without other attachment thereto, except at the belt ends as above described. The upper ends of the side-panel rear seams terminate in under-arm lacing plackets 27 and 28, the lower ends of which are on a line at the under sides of 10 the bust supports 12 and 13. The belt 25 is split about these plackets and permanently stitched therearound whereby the upper and rear portion of the belt 25 is under the contractile influence of the placket lacings. The under free hanging 15 edge of the belt 25 curves upwardly across the back of the garment to the waist line at the center of the back of the figure, and thus, through the under-arm plackets 27 and 28, control the excess under-arm and shoulder development to prevent 20 padding or rolling of the flesh above the waistline.

Initially, the garment is closed over the figure above the area 14 by some auxiliary initial fastener to relieve stress on the "zipper" fastener, herein shown as hooks and eyes 29 and 30, one set 25 29 at the central portion of the reinforcement 24, and the other set above, near the upper corner of the reinforcement. Then the slide 17 is pulled up to joint the panels 10 and 11, the front placket 15 and the under-arm plackets 27 and 28 being 30 adjusted as to openings required by experimentation. The garment is provided with the usual hose supporters 32 along its lower edge. Also, the garment is further provided with a reinforcing fabric strip 31 extending upwardly a short distance 35 from and across the lower end of the rear panel 21, between the side panels, the fabric being substantially non-stretchable, and further being less in height at its side panel junctures than the height of the elastic inserts 22 and 23, the central portion of the strip 31 being higher than at its 40 ends.

While I have herein shown and described my invention in the best form as now known to me, in minute detail, it is obvious that structural changes such as in materials, stitching, and the like, may be made without departing from the spirit of the invention, and I therefore do not desire to be limited to that precise form except as 45 may be required by the following claims.

50 I claim:

1. In a boneless foundation garment, a non-stretchable belt attached to the upper rear part of the garment and hanging freely therefrom and terminating above the waist line, said belt extending around forwardly by a widening portion, the lower part of which forward portion is below 55 the waist line, said garment having a major opening centrally down the garment front, the forward

ends of said belt being anchored in the garment portions adjacent said opening, and a front non-stretchable reenforcement tapering outwardly from the front central line of the garment both downwardly and upwardly over the abdomen to 5 points on the respective sides of the garment below the waist line, and the major portion of said reenforcement being positioned to cover that area between the ribs and pelvic bones and being in overlapping relation by its upper part with at 10 least lower parts of said belt front ends.

2. A boneless foundation garment, a non-stretchable belt attached to the upper rear part of the garment and hanging freely therefrom, said belt extending around forwardly by widening portion over the waist line, said garment having a major opening centrally down the garment front, the forward ends of said belt being anchored in the 15 garment portions adjacent said opening, and a front non-stretchable abdominal reenforcement 20 tapering from the front central line of the garment both sides to substantially point in the sides of the garment below the waist line, the upper portions of said reenforcement being in overlapping relation with at least lower parts of 25 said belt front ends, said reenforcement consisting of a series of closely spaced stitching diagonally extending above and below a horizontal line between said points and toward said center line over the entire area of the reenforcement, 30 and a non-stretchable fabric under the garment over said reenforcement area secured thereto by said stitching.

3. In a boneless foundation garment, a non-stretchable belt attached to the upper rear part 35 of the garment and hanging freely therefrom, said belt extending around forwardly by a widening portion over the waist line and extending around under and up between the bust areas of the garment, said garment having a major opening centrally down the garment front, the forward ends of said belt being anchored in the 40 garment portions adjacent said opening, and a front non-stretchable abdominal reenforcement tapering from the front central line of the garment both sides to substantially point in the sides of the garment below the waist line, the upper portions of said reenforcement being in overlapping relation with at least lower parts of said belt front ends, said reenforcement consisting of 45 a series of closely spaced stitching diagonally extending above and below a horizontal line between said points and toward said central line over the entire area of the reenforcement, and a non-stretchable fabric under the garment over said 50 reenforcement area secured thereto by said stitching.

ALICE M. RABENSDORF.

CERTIFICATE OF CORRECTION.

Patent No. 2,117,103.

May 10, 1938.

ALICE M. RABENSDORF.

It is hereby certified that error appears in the above numbered patent requiring correction as follows: In the grant, line 13, the name of the assignee of one-half interest was erroneously written and printed as Sidney J. Stevenberger, whereas said name should have been written and printed as Sidney J. Sternberger; and that the said Letters Patent should be read with this correction therein that the same may conform to the record of the case in the Patent Office.

Signed and sealed this 28th day of June, A. D. 1938.
